Patented Mar. 10, 1970

216,811

VALET RACK OR SIMILAR ARTICLE

Daniel Thomas Hallahan, New York, N.Y., assignor to
Sanjo Utility Mfg. Co., Inc., Brooklyn, N.Y.

Filed Oct. 14, 1968, Ser. No. 13,956

Term of patent 14 years

Int. Cl. D6—07

U.S. Cl. D33—8

Fig. 1

Fig. 2

Fig. 3

Fig. 4

Fig. 5

Fig. 6

FIGURE 1 is a plan view of a valet rack showing my new design;

FIGURE 2 is a rear elevational view thereof;

FIGURE 3 is a bottom plan view thereof;

FIGURE 4 is a front elevational view thereof;

FIGURE 5 is a side elevational view thereof; and

FIGURE 6 is a second side elevational view thereof.

I claim:

The ornamental design for a valet rack or similar article, substantially as shown.
